ATTORNEY

UNITED STATES PATENT OFFICE

STEPHEN A. STILWELL, OF LEBANON, OHIO

HOLDING SOCKET FOR FOUNTAIN PENS

Application filed August 22, 1928. Serial No. 301,386.

This invention relates to improvements in swivel pen-holding sockets such as are generally used on desks or writing-tables in connection with both fountain and ordinary dip pens, providing a socket-member that is mounted on a suitable base to hold the pen in a convenient swivel or pivotal position for the user to easily deposit and release or grasp it, and at the same time provide a means whereby the ink remaining on the pen-point after use will not be smeared over the surface of the desk or soil any of the papers and various other articles that are strewed or laid thereon.

The various pen-sockets in general use have only partially provided these advantages since, in the case of the ball-and-socket and other similar adjustable varieties, an accidental blow or knock from a heavy paper or book will deflect the pen-socket to a position whereby the pen will fall or fly out, or cause other inconvenience, while those providing a fixed upright or a fixed oblique-angled position for the pen-socket are either easily overturned or the pen broken off by the accidental hit or blow by a book or a heavy paper, or other moving object.

The essential purpose of my invention is to provide a self-adjusting or automatic seating or setting swivel pen-holding socket which is inexpensive to manufacture and is highly efficient in actual use, being free from the usual defects in similar devices, such as said breakage and upsetting.

Another useful purpose of my invention is to provide a swivel pen-socket which shall be capable of maintaining a predetermined fixed position and at the same time capable of yielding momentarily to any force which may operate to deflect the pen from its normal position, the pen again, automatically and instantly, regaining its normal position, whether perpendicular or inclined, when the objectionable force ceases to act and without danger of upsetting or breakage to either the pen, the pen-holding socket, or the base-support.

My invention consists, therefore, of a pen socket or tubular receptacle and a base-support, a retractile spring, the latter being pro-

vided in said base-support and connected to said pen-socket and the base provided with an upright conical projection and the bottom of said pen-socket being adapted to fit over the said conical projection and the said spring acting to maintain a definite perpendicular or obliquely-angular relation between the base and the pen-socket as occasion or fancy may require.

In the accompanying sheet of drawings, forming a part of this specification, Figure 1 is a front elevation of a self setting or righting pen-socket embodying my invention; Fig. 2, also a front elevation of the device with its upper swivel-portion deflected by some force, purposely or otherwise, from its upright normal position; Fig. 3, a vertical section taken on the line 3, 3, of Fig. 1; Fig. 4, a bottom plan view of the base-member of the device; and Fig. 5, a side elevation of an adaptation of my improved pen-socket, with its upper swivel portion definitely held or stopped at a normally oblique-angle to the base.

As illustrated in these views, the pen-socket shown may be made of any suitable material, and it consists of a base-member 1 of sufficient size, shape and weight that it will not be easily overturned when placed on a desk or writing-table, and a pen-socket 2 is yieldingly mounted thereon, extending upwardly therefrom, and preferably, but not essentially, at its center.

The base-member 1 is hollow or open bottomed and is surmounted by a frustum of a cone 12 that has a central circular or cylindrical opening 13 that extends into the open bottom or chamber 14 of said base-member.

Extending outward from the base of said cone 12 I provide a shoulder 15 that is surrounded by an annular channel or groove 16 and a skirting peripheral ring or vertical outer wall 17.

The pen-socket 2 consists of a main or body portion 3 that is adapted to telescopically contain an expansile slotted or split pen-clutch 4 of flexible hard rubber, or like elastic material, and stopped by a funnel mouth 4a. The said body portion 3 is contracted at 5 to form a cylindrical pendent extension 6

of smaller diameter and with its internal diameter the same as that of the base of the cone 12, and it is provided at its lower edge with an outwardly-extending flange 7 which rests on the shoulder 15 of the base 1, being held in yielding cushioned-contact therewith by means of a conical compression-spring 18 whose broad upper end is seated in the shoulered orifice 18^a made in the dome top 18^b of said base-member 1, and acts through the link-pin 19 which is connected at one end 20 to the spring 18 and at the other end 21 to a central downward extension 22 of a disk-bottom 23 in the said body-portion 3 of the pen-socket.

The external diameter of the flange 7 is less than that of the internal diameter of the annular ring 17 and does not contact therewith when the pen-socket is in its normal upright position, as shown in Figs. 1, 3 and 5.

When the pen-socket 2 is deflected from its normal upright position seen in Fig. 1 to an oblique-angled position seen in Fig. 2, the flange 7 drops into the channel or groove 16 and is retained in its proper relation to the cone 12 by means of the outer flange or ring 17.

The contractive tension of the retractile spring 18 draws the lower circular edge of the pen-socket into the proper frictional rolling-contact with the cone 12 so that there is no shock when the socket-member returns to normal position or duly set or checked after it has been drawn or rocked away from its normal position as seen in Figs. 1 or 5, purposely or accidentally, and the pen cannot dislodge or "fly" from seated place therein.

In Fig. 5 I have shown an inner quarter or quadrant section extension 24 at the lower end of the body-portion 2 of the pen-socket to limit the fixed upper seating of the swivel pen-socket at an inclination from the perpendicular, the lower edge of said quadrant being of the same structure as that of the lower flanged edge of the pen-socket seen in Fig. 3 and adapted to engage the same kind of a channeled formation in the dome 18^b of the base 1, but the pen-socket in this event could not advance beyond the fixed limit of said quadrant, the lower deflection of the socket being otherwise yielding under the action of the retractile spring the same as in the form seen in Figs. 2 and 3.

In Figs. 1, 2 and 5 I show a broken fragment A of a pen as it appears when in engagement with the socket-member.

The quadrant-extension 24 in Fig. 5 serves as a mask or cover for the spring and cone details seen in Figs. 2 and 3 which ordinarily may be a little unsightly.

I claim:—

1. A swivel self-setting holder-socket for fountain pens comprising, in combination, a socket-member having temporary detaining-means therein for accommodating the writ-

ing-end of the pen, a base-member having an orifice that is provided with a circular race-way-bearing for the lower end of said socket-member, resilient tension-means in said bearing-orifice and means comprising a cylindrical pendent extension at said lower end of the socket-member for pivotally coupling the latter with the said resilient tension-means in the said bearing-orifice whereby the said socket-member may be sustained upright at the desired angle above the top of said base-member in a resilient self-adjusting position and without allowing any undue tipping of the holder device, substantially as shown and described.

2. A holder-socket for fountain pens comprising, in combination, a socket-member provided with a circular lower bearing-end adapted to receive and frictionally-detain the writing-end of a pen, a base-member having a cone-circled orifice in its upper face, a perpendicular peripheral wall and an annular raceway surrounding the said cone-circled orifice, a pierced lug extending from the said lower bearing-end of the socket-member, a vertical retractile spring whose lower end is connected in said orifice with the base-member and whose upper end is attached to said pierced lug for exerting a resilient tension on said socket-member in the prompt adjustment of the latter to normal perpendicular position or at any desired angle above the top of the base-member, substantially as shown and described.

In testimony whereof I hereunto affix my signature.

STEPHEN A. STILWELL.
